United States Patent Office.

JOHN WHITLOCK, OF BIRMINGHAM, CONNECTICUT.

Letters Patent No. 64,054, dated April 23, 1867.

IMPROVEMENT IN SELF-OILING JOURNAL-BOXES.

The Schedule referred to in these Letters Patent and making part of the same.

TO ALL WHOM IT MAY CONCERN:

Be it known that I, JOHN WHITLOCK, of Birmingham, in the county of New Haven, and State of Connecticut, have invented certain new and useful Improvements in Self-Oiling Journal-Boxes; and I do hereby declare the following to be a full, clear, and exact description of the same, reference being had to the accompanying drawings, making a part of this specification, in which—

Figure 1 represents a section through one of my journal-boxes.

Figure 2 represents a plan of the inside of the upper half of the box.

Figure 3 represents a section through the two parts or halves of the journal-box, and showing the carrying-wheel for bringing up the oil from the well or reservoir, and throwing it over the journals in dotted and sectional lines.

My invention consists in combining with a shaft or journal that carries a wheel or distributor or both, and which turns in a tight journal-box, certain oil passages that communicate with the oil reservoir in the box, so that the wheel or distributor shall carry up and flow the oil over the journals, and the excess of oil flow back through the passages to the reservoir, to be again carried up, distributed, and return.

To enable others skilled in the art to make and use my invention, I will proceed to describe the same with reference to the drawings.

A B represent respectively the upper and lower halves of the box, which fit together by flanges or lugs, or both, so that they may be bolted together as at *a a*, and one recessed into the other so as to keep them true. At about the centre in length of the box there is a deep recess, *b*, in both the upper and lower halves of the box, in which a disk, wheel, or ring, *c*, on the axle, journal, or shaft, supported and turning in said box, may turn, and connected with this wheel there may be, on one or both of its faces, or attached to its perimeter, or otherwise, distributors, *f*, for carrying the oil thus brought up by the wheel from the reservoir out on to the shaft, journal, or bearing, so as to oil it throughout, or nearly so. At the ends of the under half of the journal-box there are openings *e*, and from these openings *e* passages lead to the central portion of said half, and communicate with the reservoir or recess *b*, through which openings and passages the excess of oil thrown on to the journal or shaft passes back to said recess or reservoir to be again carried up, and again distributed over the journal. The passages leading from the ends to the recess or reservoir are closed passages, and do not in any way interfere with the proper surface-bearing between the box and journal, as slots or grooves would do that are not enclosed or cast in the box, or enclosed by the box, and the frictional metal bearing, or box-metal in the box, as I propose to do. My box may be used with a down-hanger, or on a frame, or in any of the well-known ways of using journal-boxes. Openings are made in the upper half of the box for supplying the lubricating material, and in the under half for drawing off the oil or lubricator, should it at any time become necessary to do so.

Having thus fully described my invention, what I claim therein as new, and desire to secure by Letters Patent, is—

In combination with a shaft or journal having a wheel, disk, or ring attached to that portion of it that revolves in the journal-box, and with distributors for carrying the oil over the shaft or journal, the vertical end passages, and horizontal passages leading from said ends back to the recess or reservoir, for the purpose of making a self-oiling device, substantially as described.

JOHN WHITLOCK.
